UNITED STATES PATENT OFFICE.

ROBERT O. GALLINGER, OF SEATTLE, WASHINGTON.

MARINE RAILWAY.

1,027,720.

Specification of Letters Patent. Patented May 28, 1912.

Application filed November 15, 1911. Serial No. 660,479.

To all whom it may concern:

Be it known that I, ROBERT O. GALLINGER, a citizen of the United States, residing at Seattle, in the county of King and State of Washington, have invented certain new and useful Improvements in Marine Railways, of which the following is a specification.

This invention relates to railways, and is especially designed to afford improved means for transportation of railway cars across rivers, bays, etc., and particularly in situations where the construction of a bridge thereover would interfere with the water traffic or where the cost of building such a structure would be prohibitive.

The invention consists in the novel construction and combination of devices, as will be hereinafter described and claimed.

In the accompanying drawings, Figure 1 is a view in side elevation of a car transfer embodying my invention. Fig. 2 is a vertical sectional view of the drum which is employed for winding up or paying out the electrical cable when the carriage is operative.

Referring to the drawings, the numeral 5 designates a wharf or pier at one side of a body of water, and 5' a corresponding structure at the other side. Railway tracks 6 and 6' are laid upon the respective piers. Between the pier ends and at a distance below the surface of the water sufficient to allow vessels to pass thereover is a track 7 which is supported upon a rigid foundation which 35 may be comprised of track-ties 8 laid upon stringers 9 of cap pieces 10 of driven piles 11. Provided for such submerged track is a carriage comprising a frame 12 mounted upon the axles of flanged car wheels 13 and 40 surmounted by a platform 12' upon which is laid the rails 14 of a track of a length to be juxtaposed with the rails of tracks 6 or 6' when the carriage has been moved into close proximity to one or the other of the aforesaid piers. Locomotion is provided to the carriage through the instrumentality of a reversible electric motor 15 upon the carriage which is operatively connected to the axles of the car wheels 13. Such connections 45 desirably consist of bevel gear wheels 16 fixedly secured to the ends of the respective axles and driven from bevel pinions 17 mounted on a line shaft 18 which, in turn, is driven from an upright shaft 19 through 55 the agency of a pair of bevel gear wheels 20. The shaft 19 is driven through the medium

of gear wheels 21 from a shaft 22 and the latter is driven from the motor armature-shaft as by a belt 23 passing about pulleys 15' and 22' upon these shafts. The electric current to furnish power to actuate the motor is derived from any suitable source and is transmitted by insulated circuit wires + and - extending through a cable 24 which is wound about a drum 25 rotatable upon a shaft 25' positioned on the carriage. The ends of the circuit wires at the carriage are connected to terminal rings 26 and 26' (Fig. 2) secured to the outside of the drum web 25" and make electrical connection with said motor by conductor wires 27 and 28 through brushes 27' and 28' in continuous contact with the rings 26 and 26'.

In the drawings, I show diagrammatically a bipolar switch 29 which is adapted for controlling the motor circuit, but it is to be understood that other circuit breaking and connecting switches may be utilized for the purposes of this invention.

In the travel of the carriage from the pier 5 in the example, to the pier designated by 5', the cable 24 is wound upon the drum 25 and when the carriage is going in the contrary direction the cable is unwound from the drum. To rotate the drum to accomplish these ends, there is provided a rope 30 fastened at its ends to some stationary objects as, for instance, to the piles 5" and 5'" of the piers and in alignment with the track upon which the carriage travels. 35 From the above-mentioned pier piles the rope passes about guide sheaves 31 upon the carriage and thence is led by peripheral grooves provided in the drum about the latter. By such rope connections it is apparent that the drum will be rotated in one circular direction or the other to wind up or pay out said cable to correspond with the changing positions of the carriage.

At the opposite ends of the carriage are 100 bell-crank levers 32 and 32' respectively fulcrumed by pivotal pins 33 to chairs 34 secured to the carriage frame. One arm of each of said levers projects beyond the adjacent end of the carriage and terminates in 105 a hook, as 35, or 35', which is arranged to engage in a socket plate 36, or 36', secured to the pier when the carriage is moved thereagainst for the purpose of latching the carriage against accidental movement away 110 from a pier and more especially when a car is being shifted to or from the carriage with

respect to the piers. The other arms 37 and 37' of said levers are directed upwardly, as indicated in Fig. 1.

38 represents a car loaded upon the carriage. At or near the ends of the car are vertically disposed rods 39 extending through the car floor and normally held in their most elevated positions, as by means of springs 40 acting between the rod shoulders 39' and guides 41 near the lower ends of the rods. These rods are positioned so that they will be in the same vertical plane with the aforesaid lever arms 37 and 37'.

43 represents a trolley wire above the track upon a pier and a similar trolley wire 44 is employed therewith on the carriage to connect with same when the carriage is secured to a pier.

The operation of the invention may be explained as follows: When the carriage is at one end of its travel as, for example, at the right hand side of the view (Fig. 1) and with the hook 35 of the lever 32 engaged in the socket plate 36 of the pier 5, a car is then propelled by its own driving mechanism to move the car onto the carriage. As the car thus travels the operator at the rear end pushes the rod 39 thereat downwardly so as to engage against the lever arm 37 whereby the arm will be swerved in the direction of the car's movement to tilt the lever 32 so that the hook 35 of the same will be withdrawn from socket plate 36 to release the carriage. The above described position of the lever is indicated by broken lines *a* in the drawings. When the carriage has been thus released from pier 5, the motor 15 is operated to effect the propulsion of the carriage to the other pier 5' and upon arriving thereat the hook 35' of the other lever is automatically engaged in the socket plate 36' upon the other pier. The car is then moved by its propelling machinery from the carriage onto the track 6'.

45. What I claim is—

1. The combination with railway tracks at opposite sides of a body of water, and a railway track submerged in said body of water, of a wheeled carriage mounted for

travel upon the last named track and between the terminals of the first named tracks, a railway track upon said carriage, power means for effecting the travel of the same between said terminals, and means for securing the carriage at the ends of its travel.

2. The combination with railway tracks at opposite sides of a body of water, and a railway track submerged in said body of water, of a wheeled carriage mounted for travel upon the last named track, a railway track upon said carriage, power means for effecting the travel of the same between the terminals of the first named tracks, means for automatically securing the carriage at the ends of its travel, and means operated from a car for disengaging the carriage securing means.

3. The combination with railway tracks at opposite sides of a body of water, and a railway track submerged in said body of water, of a wheeled carriage mounted for travel upon the last named track, a railway track upon said carriage, power means operable through the wheels of the carriage for effecting the travel of the same between the terminals of the first named tracks, and means for securing the carriage at the ends of its travel.

4. The combination with railway tracks at opposite sides of a body of water, a railway track submerged in such body of water, a wheeled carriage operable upon the submerged track, means for effecting the locomotion of the carriage, a railway track on the carriage, hooked levers provided at opposite ends of the carriage, and stationary socket devices in proximity to the ends of the first named tracks and disposed to be engaged by the hooks of the respective levers, of a car, and manually operated means provided upon the car for engaging said levers whereby the same are actuated to disengage the levers from said socket devices.

ROBERT O. GALLINGER.
